UNITED STATES PATENT OFFICE.

PAUL P. STOKER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

REISSUED

Application filed April 17, 1928. Serial No. 270,619.

My invention relates to railway traffic controlling apparatus, and particularly to apparatus of the type comprising a coding device located at a central station, such as a 5 despatcher's office, for delivering control codes to a pair of line wires for the control of governing devices located at points remote from the despatcher's office, and which devices in turn control the supply of indication codes 10 to said line wires for the actuation of indication means in the despatcher's office.

One system of apparatus operating in the manner described is disclosed and claimed in an application for Letters Patent of the 15 United States, Serial No. 254,684, filed February 16, 1928, by Clarence S. Snavely, for railway traffic controlling apparatus, and my present invention relates to an improvement on a portion of the apparatus disclosed in said 20 application.

I will describe one form of apparatus embodying my invention, and will then point out the novel features thereof in the claim.

The accompanying drawing is a diagrammatic view showing one form of railway traffic controlling apparatus embodying my invention.

Referring to the drawing, the reference character A^A designates a coding device located at a train despatcher's office and arranged at times to supply control codes to a pair of line wires 66 and 66^a for the control of traffic governing devices located at points remote from the despatcher's office and not 35 shown in the drawing. The coding device A^A is controlled in part by three manually operable keys K^1 , K^2 and K^3 , arranged when operated to connect terminal B of a source of energy not shown in the drawing with terminals 1, 2 or 3, respectively, of the coding 40 device.

The details of the coding device A^A are omitted from the drawing for the sake of simplicity, but these details are completely 45 disclosed in the Snavely application identified above, it being sufficient for present purposes to state that when key K^2 is operated, the coding device delivers to line wires 66 and 66^a, a control code which clears certain signals at a remote point; when key K^3 is operated certain other signals at said point are cleared; and when key K^1 is operated all signals at said point are restored to the stop position.

Located also at the despatcher's office are 55 two selectors S^9 and S^{10} , each comprising a contact which is closed for a brief interval when the winding of the selector is supplied with a predetermined indication code. The selectors S^9 and S^{10} are supplied with energy 60 from a battery g^A under the control of contact 139 of a relay E^A which faithfully follows the impulses of indication codes supplied to the line wires.

The selectors S^9 and S^{10} are responsive to 65 the condition of the track circuit associated with the signals governed by keys K^1 , K^2 and K^3 , selector S^{10} being operated to close its contact when a train enters this section, and selector S^9 being operated to close its contact 70 when the train leaves the track section, as described in the Snavely application referred to hereinbefore. When selector S^9 is operated, current is supplied to the left-hand winding of a relay U from terminals B and 75 C to move armature 190 to a left-hand position in which it is illustrated in the drawing. When the armature occupies this position, lamp 192 is lighted to indicate to the despatcher that the section through which traffic is governed by the signals controlled by keys K^1 , K^2 and K^3 is unoccupied. When selector S^{10} is operated, however, current is supplied to the right-hand winding of relay U , 80 armature 190 is swung to the right and lamp 191 is lighted to indicate that the section is occupied by a train.

In systems of the type here involved it is usual to control the signals associated with a section of track in such manner that 90 when a train occupies the section all signals will indicate stop, but that when the train leaves the section, any signal or signals which were cleared before the train entered the section will return to the proceed 95 position. This is usually called "semi-automatic" control. It is sometimes desirable, however, to introduce what is known as "stick" control of such signals. This is accomplished by arranging the signal control 100 so that after a train enters and leaves a section, the signals will remain at stop until the despatcher takes suitable steps to again clear a signal.

In order to provide for stick control of the signals controlled by keys K^1 , K^2 and K^3 , in the apparatus here shown, I have provided a 105 manually operable push button Y which is

arranged when closed to connect the contact of selector S^{10} in parallel with key K^1 .

In explaining the operation of the apparatus, I will assume that push button Y is closed and that the despatcher has operated one of the keys K^2 or K^3 to clear a signal. If, now, a train enters the track section associated with such signal, an indication code will be delivered to the line wires 66 and 66^a which operates selector S^{10} . When the contact of this selector closes relay U is reversed, of course, but in addition, terminal B is connected through the contact of selector S^{10} , push button Y and wire 80, with terminal 1 of coding device A^A . As a result the device A^A supplies to the line wires the control code which restores the signals to stop, and after the train leaves the section all signals remain in the stop position.

It will be seen, therefore, that by the use of apparatus embodying my invention, either semi-automatic control or stick control of the signals shown in the Snavely application may be obtained, and that these desirable results are accomplished with the addition of

comparatively little apparatus in the despatcher's office only, and without affecting the operation of the remainder of the apparatus.

Although I have herein shown and described only one form of railway traffic controlling apparatus embodying my invention, it is understood that various changes and modifications may be made therein within the scope of the appended claim without departing from the spirit and scope of my invention.

Having thus described my invention, what I claim is:

In combination, a pair of line wires at times supplied with an indication code, a coding device for at times supplying a control code to said line wires, a manually operable key for controlling said coding device, a selector responsive to said indication code and comprising a contact, and manually controlled means for at times connecting the contact of said selector in parallel with said key.

In testimony whereof I affix my signature.

PAUL P. STOKER.
